UNITED STATES PATENT OFFICE.

JOHN FREDRICK KAISER, OF MADISON, WISCONSIN, ASSIGNOR TO BURGESS BATTERY COMPANY, A CORPORATION OF WISCONSIN.

SEMAUTOMATIC SAFETY FEED FOR REDRAWING PRESSES.

Application filed July 7, 1922. Serial No. 573,478.

To all whom it may concern:

Be it known that I, JOHN F. KAISER, a citizen of the United States, residing at Madison, in the county of Dane and State of Wisconsin, have invented certain new and useful Improvements in a Semiautomatic Safety Feed for Redrawing Presses; and I do hereby declare the following to be a full, clear, and exact description of the invention, such as will enable others skilled in the art to which it appertains to make and use the same.

My invention is an improvement in feeds for redrawing presses, and relates particularly to semi-automatic feeds. With the usual construction of redrawing press, the articles to be redrawn are fed between the die and the reciprocating punch, and efficiency requires that there be an article in the die properly positioned for engagement by the punch at each reciprocation thereof. The articles are customarily fed by hand, the operator placing the articles directly in the dies, and in order to feed the articles, the hand or fingers of the operator must be introduced for a moment between the punch and the die. If the operator is negligent, or is a little slow in withdrawing the hand or if the press operates for any reason unexpectedly, the operator's hands or fingers are caught between the punch and the die, and serious injury may result.

In the present invention, I provide a means which is semi-automatic, for feeding the articles in succession to the dies, normally operative, and controlled to inoperative position by the movement of the punch, and wherein the services of an operator are required only at a distance from the punch, to place the articles in the feeding means. I also so construct the feeding means, that neither speed nor any great degree of care is necessitated in the initial placing of the articles in the feeding means, the operation of the feeding means itself centering the articles for correct feeding.

In the drawings;

Figure 1 is a plan view of the improved feeding means;

Fig. 2 is a front elevation;

Figs. 3 and 5 are sections on the lines 3—3 and 5—5 respectively of Fig. 1; and

Fig. 4 is a view similar to Fig. 3, showing the parts in another position.

In the present embodiment of the inven-

tion, the articles indicated at 1, in the present instance zinc battery cups or cans, are fed in succession into dies 2 of usual construction, with which cooperate punches 3, the said punches drawing the cans or cups through the dies to properly shape the same. The dies are supported by the usual die-holder or bolster plate 4, the said holder having an opening 5 below each die, through which the completed cup is discharged. The punches are carried by a punch holder 6 of usual construction, and a feed chute 7 extends forwardly from the die holder, the said chute having a guideway 8 for each punch, the cups which are to be fed beneath the punch moving in the adjacent guideway.

The guideways are of a length to hold a number of cups, in the present instance five, exclusive of that upon the die, and each guideway has at its top overlying flanges 9, which prevent upward movement of the cups, and hold them in the guideways. The cups are fed toward the punches, by means of a pusher bar 10, which extends transversely of the chute at the outer end thereof, and transversely of the outer end of each guideway. The pusher moves in the outer ends of the guideways, on the bottoms thereof, and simultaneously moves all the cups in the guideways toward the punches, when the said pusher bar is moved toward the punches in a manner to be presently described. Coil springs 11 are connected with the ends of the pusher bar, and with hooked brackets 12 extending from the die holder in the opposite direction to the chute, and these springs act normally to draw the pusher bar toward the punches. The pusher bar is moved outwardly away from the punches, by means of cam plates 13 depending from the ends of the punch holder 6. These cam plates have their lower ends beveled as shown, and the beveled lower ends are adapted to engage rollers 14 on blocks or brackets 15, connected with guide rods 16, which are secured to the ends of the pusher bar. These guide rods move through guides 17 and 18 on the die holder and they constrain the pusher bar to move squarely toward and from the punches, without any lateral movement.

A feed plate 19 is arranged above the chute at the outer ends of the guideways, and the said plate is provided with an opening 20 through which an article 1 may pass, at each guideway. This plate is fixed, and

105

110

the operator merely drops the articles into the openings 20 above mentioned. In each guideway the pusher bar 10 carries a shutter 21, in the form of a block on the upper face of the bar. The blocks have their upper faces at approximately the level of the tops of the cups in the guideway, and the lower ends of the cups in the openings 20 rest upon the blocks or shutters, which prevent such cups from dropping into the guideways. The shutters move with the pusher bar, and when the pusher bar is in its forward position, that is in position nearest the punches, the shutter is beneath the openings 20. When, however, the pusher bar moves rearwardly away from the punches, the shutter uncovers the openings 20, and permits the cups to drop into the guideways.

The operation of the improvement is as follows:—With the parts in the position of Figure 3, a cup in each guideway is in position beneath the adjacent punch, and there is a cup in each opening 20 of the feed plate. When now the punch holder descends, the cups in the dies are drawn through the dies. At the same time, the cam plates 13 engage the rollers 14, and the pusher bar is moved away from the punches, the roller riding up the bevelled ends of the cam plates. The shutters are moved out from beneath the articles in the openings 20, and such articles drop down between the shutters 21 and the cups in the guideways. When the punches move upward, the cam plates gradually release the rollers 14, and the springs 11 which are under tension, contract and move the pusher bar together with the shutters and the cups in the guideways toward the punches, bringing another cup into each die. The operator merely places the cups in the openings 20, and since there is ample time, no speed and no particular care is required in the placing of the cups. At no time is it necessary for the operator to insert his fingers between the punch and the dies, and as a consequence there is no liability to injury. When the punches ascend, the cups which have been redrawn are stripped off. In the present drawing, seven punches, and seven guideways are shown. It will be understood however, that in actual operation all of the punches and guideways may not be utilized, and any number may be utilized, from one to the entire number. Since the moving mechanism of the feed is coil springs, injury is not liable to result from any stoppage, since the springs will exert only a moderate tension.

In operating the feed for the press, when the punches 3 engage the cups, the cups bulge between the punch ends and the dies. This bulging is sufficient in each cup to force all of the cups in the adjacent guideway rearwardly, that is toward the feed plate 19. From this results that the cup

which is being fed into the opening 20 of the feed plate cannot fall freely into normal position to be fed toward the punch. Such cup is liable to catch upon the preceding cup in the guideway, so that the feeding operation is interfered with. In order to overcome this difficulty, I provide the mechanism shown more particularly in Figs. 3 and 4, for holding the cups in the guideways against the pressure from the bulging of the cup being operated upon. The said mechanism comprises a pin 25 for each guideway, each pin being mounted to move vertically in a bar 26 arranged transversely of the magazine between the feed plate and the punches. A pin is provided for each guideway, and these pins are so placed that they will engage behind the forward edge of the last cup in the chute just before the punches descend, to hold the cups against the bulge of that cup being operated upon. These pins are normally pressed downward, by springs 27 which encircle the pins between an annular shoulder 28 on the pin and a plate 29 secured to the top of the bar, it being understood that the bar has vertical openings for receiving the pins. Each of the openings in the bar is reduced below the shoulder 28, to limit the downward movement of the pin, and the pins are bevelled on the side adjacent to the feed plate, so that when the feed plate moves the cups toward the punches, the pins will be lifted by the cups or cans to permit said cups or cans to pass. The pins are held from rotation, so that the bevelled face is always properly positioned, by means of a key 30. This key is common to all the pins, engaging a keyway in each pin. When the cups are fed toward the punches, the pins are lifted and dropped just within the forward part of the outermost cup. When now the punches descend, the pins hold the cups against rearward movement away from the punch, so that the articles may be properly fed into the magazines.

I claim:

1. In a press of the class described, the combination with the punch and the die, of means for feeding articles toward the die, means controlled by the movement of the punch toward the die for moving said feeding means away from the die thereby to permit the insertion of an article between the said means and the die to be fed toward the die when the punch moves away from the die, and yielding means for moving said feeding means to feed the articles toward the die.

2. In a press of the class described, the combination with the punch and the die, of normally operative means for feeding a plurality of articles toward the die simultaneously, means controlled by the movement of the punch toward the die for moving the

feeding means away from the die, means for supporting an article in position to be dropped between the feeding means and the die, and arranged to be released by the movement of the feeding means away from the die, and yielding means for moving said feeding means to feed the articles toward the die.

3. In a press of the class described, the combination with the punch and the die, of spring-pressed means for moving the articles toward the die, and means controlled by the movement of the punch toward the die for moving the said means away from the die against the spring tension.

4. In a press of the class described, the combination with the punch and the die, of spring-pressed means for moving a plurality of articles toward the die simultaneously, means controlled by the movement of the punch toward the die for moving the said means away from the die, means for supporting an article in position to be dropped between the feeding means and the die and arranged to be released by the movement of the feeding means away from the die, and means for holding all of the articles in position when the feeding means is moved away from the die.

5. In a press including a battery of dies and punches and a common means for reciprocating the punches, the combination of feeding chutes for the several dies arranged alongside each other, a common means for feeding a plurality of articles in each of the several chutes toward the dies simultaneously, yielding means for moving said feeding means to advance said articles toward said dies, and means controlled by the movement of the punches toward the dies for moving the article moving means away from the dies.

6. In a press including a battery of dies

and punches and a common means for reciprocating the punches, the combination of feeding chutes for the several dies arranged alongside each other, a common spring-pressed means for moving a plurality of cup-shaped articles in each of the several chutes toward the dies simultaneously under the action of the spring pressure, means controlled by the movement of the punches toward the dies for moving the article moving means away from the dies, means adapted to engage the inner edge of certain of the cup-shaped articles to hold all of the articles in position when said feeding means is moved away from the dies, and means for supporting articles above the feeding chutes in position to be dropped into said chutes adjacent to the moving means and controlled to release position by the movement of the moving means away from the dies.

7. The combination with a die and a punch, of spring-pressed means for feeding articles toward the die and punch under the action of the spring pressure, and means responsive to the movement of the punch toward the die for moving said feeding means away from said die and punch.

8. In a press of the class described, the combination with the punch and the die, of spring-pressed means for moving the articles toward the die under the action of the spring pressure, means controlled by the movement of the punch toward the die for moving the said means away from the die, and means engaging the outermost of the series of articles for holding the said articles from movement away from the die during the descent of the die, said means being controlled to inoperative position by the movement of the articles toward the dies.

In testimony whereof I affix my signature.

JOHN FREDRICK KAISER.
